(57) **CLAIM**

The ornamental design for a plug connector terminal, as shown and described.

DESCRIPTION

FIG. 1 is a top perspective view of a plug connector terminal showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is an exploded view thereof, in use condition;

FIG. 9 is a perspective view thereof, in use condition; and, FIG. 10 is a cross-section view of the plug connector terminal of FIG. 9 along line 10-10.

The broken lines in FIGS. 8, 9, 10 are included to show unclaimed environment only and form no part of the claimed design.

1 Claim, 8 Drawing Sheets
